5PCS Watermelon Side Marker Lights for Trucks & Trailers, Generic. (Jun. 28, 2025), [site visited Sep. 17, 2025]. Available from Internet, <URL: Retrieved from <https://www.amazon.com/Watermelon-Trailers-12V-24V-Waterproof-Multi-Color-Accessories/dp/B0F8QYG5XB>>.*

Primary Examiner — Natasha Vujcic

CLAIM

The ornamental design for a truck light, as shown and described.

DESCRIPTION

FIG. 1 is a front, top and right-side perspective view of a truck light showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, bottom and left-side perspective view thereof.

The broken lines throughout the drawing figures depict portions of the truck light that form no part of the claimed design.
